UNITED STATES PATENT OFFICE.

WILHELM BACHNER, OF STUTTGART, GERMANY.

APPARATUS FOR FILLING BOTTLES.

SPECIFICATION forming part of Letters Patent No. 634,793, dated October 10, 1899.

Application filed October 29, 1898. Serial No. 694,904. (No model.)

To all whom it may concern:

Be it known that I, WILHELM BACHNER, a citizen of the German Empire, residing at Stuttgart, in the Kingdom of Würtemberg, 5 Germany, have invented certain new and useful Improvements in Apparatus for Filling Bottles; and I do hereby declare the following to be a full, clear, and exact description of the invention, such as will enable others skilled 10 in the art to which it appertains to make and use the same.

This invention relates to improvements in apparatuses for filling bottles and the like with effervescent drinks, such as beer, from 15 larger receptacles, such as casks and the like, under the pressure of carbonic acid or air.

As is well-known, when gaseous liquids under pressure are drawn into open vessels a partial escape of the gas takes place—for instance, in the case of such liquids as contain 20 carbonic acid—owing to frothing or foaming. This is avoided in the apparatus which forms the subject of the present invention by the racking or drawing-off device, and the vessel 25 to be filled is placed temporarily in communication with a vessel standing under pressure by means of movable pistons, so that only a slight difference of pressure exists between the vessel to be emptied and the one 30 to be filled. This improved drawing-off device is shown in the accompanying drawings, Figure 1 being a front elevation of same; Fig. 2, a plan view; Fig. 3, an end view, partly in section. Figs. 4 to 6 are separate detail 35 sectional views, on an enlarged scale, of the parts of the apparatus on which the invention is based.

The cask B to be emptied is connected in the ordinary manner by means of a back-pressure valve b', pipe b, reducing-valve b², and the like with a carbonic-acid container C and also by means of a pipe c with a tap E, from which a further pipe e' is connected with the bottle-filling tube G, which extends 40 almost to the bottom of the bottle F, by means of a pipe-nozzle g' and a screw-nut g, Fig. 5. A further tube H is located over the tube G and carries at the bottom a filling-plug J for the bottle, said tube H being tightly jointed 45 onto the outside of the tube G by means of a stuffing-box h and having at the sides a nozzle and a three-way cock h' with two small

tubular connections. On one of these latter a tube i is attached, which is connected with a pipe k, situated in a vessel K.

The vessel K is mounted on a bracket K', 55 attached to the frame A of the apparatus and is closed at the top by a cover or cap M, in which a piston m, having a rod m', is air-tightly mounted. On the second tubular attachment 60 of the three-way tap h' a pipe c' is attached, which leads directly to the carbonic-acid container C, and thus serves at the commencement of the filling of the bottle—that is to say, before any pressure exists in the vessel 65 K—to convey carbonic acid directly to the bottle F.

The bottle F is placed on a movable bottle-holder or dish R (normally in an elevated position) after it has been closed by means of the 70 plug J, which dish is fixed on a slide P, which is mounted so as to be vertically adjustable on a slide-bar N by means of two sliding jaws p p' and which is connected with a lever D at the top by means of a chain d'. The lever D is mounted on the plug e of the tap E and is so adjustable by means of a counter-weight d that when the bottle is placed on the dish R the latter, together with the bottle, sinks or descends and the lever D is turned 75 and the cock E automatically opened. The beer then flows out of the cask B through the pipes c and e', cock E, and filling-tube G into the bottle, while after the cock h' of the filling apparatus has been opened air escapes 80 from the bottle through the pipes H and i and the pipe k into the vessel K. The air in the latter is thus compressed, corresponding to the pressure of the carbonic acid or the air 85 acting in the cask, and thereby the piston m, 90 located in the cover M of the vessel K, is raised as soon as the pressure has reached a certain height.

Several small openings o are formed in the sides of the cylindrical part O of the cover M 95 at an equal height, Fig. 4, through which holes the compressed air can partially escape out of the vessel K after the piston m has passed said holes, after which the piston m immediately descends under the action of a 100 spring-actuated valve m², arranged at the end of the hollow rod m', and thereby closes the openings o. As soon as the piston m moves past the opening o there is a sudden outrush-

ing of air from the vessel K due to the excess of pressure in the latter, and thus is there a tendency to the production of a partial vacuum in said vessel, which tendency causes the 5 piston to start to sink suddenly of its own weight. The effect of this outrushing of air is usually so great that the said piston would, unless provided against, be lowered with considerable force, and it is for the purpose of 10 preventing this that the valve m^2 is employed. This valve is so adjusted by its spring that as soon as the pressure beneath the piston m sinks below the normal the valve is caused to open, and air immediately passes 15 in and through tube m' to supply the deficiency on the under side of the piston. In this way the downward movement of said piston is made easy and gradual, with no tendency to back pressure either in tube i or the 20 bottle being filled. When the bottle is filled it is raised, together with the filling device G H and the pipe e' after the tap h' has first been closed. The tap E on the removal of the bottle is automatically closed by the counterweight d on the lever D and on a fresh 25 empty bottle being placed on the dish R is again automatically opened. As soon as an empty bottle has been placed on the dish the tap h' is then opened, whereby the bottle communicates with the vessel K and stands under pressure in such a way that the beer flowing into the bottle encounters a resistance and any frothing or foaming is avoided. By 30 altering the weight of the piston m the amount of pressure in the vessel K and bottle F may be regulated.

In case of the overflowing of the bottle—that is to say, if the same be removed too late—the beer passes into the vessel K, and 35 in order to allow of the same being removed therefrom a drawing-off nozzle, with a tap k' and pipe l , is arranged on the same, through which the beer can be run off into a vessel or the like placed beneath, or it may also be 40 drawn off into any bottle. In the latter case a draw-off tap l' , with an air-escape tap l^2 , is provided on the pipe l .

The parts of the drawing-off apparatus are attached to the partition-wall A of a stand, 45 which can be conveniently attached to any racking or drawing-off apparatus. A horizontal table-plate A' is arranged on the lower part of the stand A to allow of the bottles being placed thereon.

50 I declare that what I claim is—

1. In an apparatus for filling bottles, the combination with a pressure-tank adapted for connection with a cask of beer or the like, of a

tap normally closed by a plug or valve means for connecting said tap with the cask, a movable bottle-holder for opening said tap by the weight of an empty bottle, means for simultaneously closing the tap and raising the bottle-holder on the removal of the filled bottle, a filling-tube for the bottle, and a tubular connection between said filling-tube and the tap. 60

2. In an apparatus for filling bottles, the combination with a pressure-tank adapted for connection with a cask of beer or the like, of a 65 tap having a plug for opening and closing the same, and means for connecting the tap with the cask, a movable bottle-holder, a lever on the tap-plug, a chain connection between said lever and bottle-holder whereby the latter is carried downward and the tap simultaneously opened by the weight of an empty bottle, means for simultaneously closing the tap and raising the holder on the removal of the filled bottle, a filling-tube for 70 the bottle, and a tubular connection between said filling-tube and the tap. 75

3. In an apparatus for filling bottles, the combination with a pressure-tank adapted for connection with a cask, of a tap having a plug 80 for opening and closing the same, and means for connecting the tap with the cask, a movable bottle-holder, a lever on the tap-plug, a chain connection between said lever and bottle-holder whereby the latter is carried downward and the tap simultaneously opened by the weight of an empty bottle, means for simultaneously closing the tap and raising the holder on the removal of the filled bottle, a filling-tube for 85 the bottle, an air-escape tube 90 surrounding said filling-tube, and a counter-pressure device connected with said air-escape tube. 95

4. In an apparatus for filling bottles, the combination with pressure devices, and drawing-off devices from a keg of beer or the like, of means for filling a bottle, an air-escape for the bottle, means for controlling said escape, a tubular connection between the air-escape and the pressure devices, and a counter-pressure device comprising a closed vessel connecting with the air-escape and having an air-escape opening, a piston in said vessel having hollow stem, and a valve on the stem operating substantially as described. 100

In testimony whereof I affix my signature in presence of two witnesses.

WILHELM BACHNER.
